UNITED STATES PATENT OFFICE.

BENJAMIN H. LEWIS, OF CORAL, MICHIGAN.

MACHINE FOR CUTTING MITERS.

SPECIFICATION forming part of Letters Patent No. 240,737, dated April 26, 1881.

Application filed October 18, 1880. (No model.)

To all whom it may concern:

Be it known that I, BENJAMIN H. LEWIS, of Coral, in the county of Montcalm and State of Michigan, have invented an Improvement 5 in Devices for Cutting Miters, of which the following is a specification.

The nature of this invention relates to certain new and useful improvements in machines for cutting miters at any desired angle, by 10 means of which the necessary angle can readily be determined, and by which an angle with a "rake" can be readily cut.

The invention consists in the peculiar construction of the various parts and their combinations, as more fully hereinafter described. 15

Figure 1 is a perspective view of my improved machine. Fig. 2 is a vertical section through the extended wing-guides. Fig. 3 is a vertical section on line xx , Fig. 1. Fig. 4 is 20 a plan of the top of the bed.

In the accompanying drawings, which form a part of this specification, A represents the base or bed of the device, to which the operating parts are secured. 25

B represents two rectangular frames, which are secured in parallel positions, as shown, to the base by means of the angle-irons a and suitable screws. Between these two frames the gate C has a vertical motion, the frames 30 acting as guides therefor.

To each side of the girt D is secured a downwardly-projecting guide, b , which embraces the sides of the saw midway between the two ends of the gate, to act as guides to prevent 35 the saw from buckling. The saw E is of uniform thickness and without a back, and has near its upper edge, and parallel thereto, slots c , which, engaging with stops d , secured to the front and rear ends of the gate C, secure 40 the saw to the gate without interfering with the reciprocation thereof.

F and F' are two radially-swinging guides, pivoted with a common pivot, e , to the bed A at a suitable point between the frames B, and 45 so as not to obstruct the working of the device. These guides are adjusted to the desired position by set-screws f , which enter the radial slots g in the circular iron plates H, secured to the face of the bed. To give the guides the 50 necessary steadiness they are secured to the blades or bearing-plates I, which slide or rest

upon the plates H, while the inner ends of the guides rest upon suitable plates, K, which brings them to a level position.

Rising from the guides F F' are the vertical 55 standards L L', the former of which is provided with a suitable dog, M, capable of vertical adjustment by means of any of the well-known devices. The standard L' is provided with a rest, N, also capable of a vertical adjustment.

A dog or support, O, is secured to guides F F', and is capable of lateral adjustment.

A bolt, P, passing through the bed of the device, is intended to secure the machine to 60 any suitable foundation.

The scope of this device is much larger than that of any ordinary miter-box.

If it is desired to cut an ordinary miter, the material to be operated upon is secured to the 70 guides by the dogs M and O, while the rest N is elevated or depressed out of the way, so that the work will rest snugly against the face of the guides. After the guide F or F' has been properly adjusted to the miter or angle 75 desired, the set-screw f is tightened, thus rigidly securing the guide to place. A reciprocation of the saw, which is gradually depressed by the gravity of the gate C, will sever the material presented to it. 80

To cut a "rake" the material to be operated upon, in addition to the dogging hereinbefore described, is supported upon the rest N, which is adjusted vertically so as to give the desired 85 rake.

While I show two sets of guides, it will be seen that the device would be operative with but one, although with two much less handling of material is required, and for which last object I pivot the device at P to a support, 90 so that it can be turned for the introduction of heavy work not easily handled.

I am aware that an adjustable rest or support for the material to be sawed at a rake or bevel, in connection with two guide-posts for 95 a horizontally-reciprocating saw, said posts being mounted on and turning with a circular metal plate marked with radial lines, whereby the material may be sawed at any desired rake and any desired angle, has heretofore been employed, and I therefore lay no claim, broadly, 100 to such construction, my invention being con-

fined to the details of construction, in which the saw-guides are stationary and the guides for the material are movable radially, whereby the circular movement of the saw-guides is dispensed with, which is objectionable where power is applied to operate the saw, as it requires an adjustment of the machine relative to the power every time the position of the saw-guides is changed.

10 What I claim as my invention is—

1. In a mitering-machine, the combination, with the stationary guides B and horizontally-reciprocating saw E, of the radially-swinging guide F, vertically-adjustable dog M, laterally-

adjustable dog O, and vertically-adjustable 15 rest N, substantially as described, and for the purpose set forth.

2. In a mitering-machine, the combination, with the radially-swinging guide F, of the vertically-adjustable dog M, laterally-adjustable 20 dog O, and vertically-adjustable rest N, substantially as described, and for the purpose set forth.

BENJAMIN H. LEWIS.
